UNITED STATES PATENT OFFICE

ISIDOR KITSEE, OF PHILADELPHIA, PENNSYLVANIA.

COLOR PHOTOGRAPHY.

1,209,453.

Specification of Letters Patent. Patented Dec. 19, 1916.

Application filed March 3, 1916. Serial No. 31,879.

To all whom it may concern:

Be it known that I, ISIDOR KITSEE, a citizen of the United States, residing at Philadelphia, in the county of Philadelphia and State of Pennsylvania, have invented certain new and useful Improvements in Color Photography, of which the following is a specification.

My invention relates to an improvement 10 in color photography, and has more special reference to the production of color blanks for photographic purposes.

My invention may be practised with stationary blanks but its great value is most 15 apparent in color photography, for moving picture films.

It is the aim of my invention to produce the required color media on the photographic blanks and I elect, that the media 20 should be of the three color type but it is obvious that the number of colors may differ to suit the requirements, and I elect that the media should represent the following colors:—red, green, blue-violet, but it is obvious 25 that these colors may be replaced by required color combination.

In my experiments I have found, that the greatest draw back in producing color blanks for color photography, that is in producing 30 the multi-colored screen, specially if such color screen should be an integral part with the sensitized blank, is that the minute color particles are usually not distributed in required order. It is the aim of my invention 35 to obviate such difficulties and to produce a photographic blank or film, having integral therewith the multi-colored screen.

To illustrate some forms my invention may take I have reference to the accompanying 40 drawing.

In this drawing, Figure 1 is a plan view of part of a screen surfaced with squares of different color, to be used for the purpose of photographically reproduced therefrom 45 printing surfaces. Fig. 2 is a sectional view of a device to produce printing rollers from the color screen. Fig. 3 is a top view of the printing rollers and a film adapted to have printed thereon with the aid of these rollers 50 the different colors. Fig. 4 is a side elevation of Fig. 2. Fig. 5 is a diagrammatic view of part of Fig. 4. Fig. 6 is a top view of one of the diaphragms illustrated in Figs. 2, 4 and 5.

55 In Fig. 1, which represents a three-color screen, 21 indicates the red, 22 the green and

23 the blue-violet, but it is obvious that other colors may be added or substituted if so required.

In Fig. 2, 1 is the base, 2 the movable frame work, 3 the guides for said frame work. Supported by this frame work is the diaphragm 4, 5 is a color filter, 6 the lens system, 7 the sensitized roller, 8 the shaft on which this roller is supported, 9 the shaft 60 connecting through gearing with the shaft 8 at one end and through gearing with the shaft 10 at the other end. Fastened to the shaft 10 is the driving gear wheel 11 provided with the handle 24. 12 is a stationary 65 rack engaging the gear wheel 11 and fastened to the base 1, 13 is the color screen from which the printing rollers are reproduced.

In Figs. 3, 14, 15 and 16 are the printing 70 rollers connected to each other through the gears 17, 18 and 19 and their intermediates, 20 is the film.

In Fig. 4, 1 is the base, 2 the frame, 4, 4^a and 4^b diaphragms, 5, 5^a and 5^b color filters, 80 each of different color, 6, 6^a and 6^b lens system, 8, 8^a and 8^b the shafts carrying the sensitized rollers, 9 the shaft connecting through gearing the rollers with the shaft 10, 11 the driving gear wheel connecting the 85 shaft 10 with the stationary rack 12 of the base 1.

In Fig. 5, 13 is the color screen, 4 the diaphragm, 5 the color filter, 6 the lens system and 7 the sensitized roller. 90

In Fig. 6, 4 is the opaque diaphragm with the transparent part 25.

The mode of operation is as follows:—A surface of the required size is provided with the required color scheme, in the shape of 95 squares, triangles or otherwise in a manner so that one color should always precede and be succeeded by a different color. When the three color scheme is used, it is preferred that the different colors should be distributed 100 about equal to the scheme as illustrated in Fig. 1. The surface of each of the three comparatively small rollers is then sensitized for panchromatic work and these rollers are placed in position in the device as described. 105 Each roller is provided with a separate lens system and is also provided with a color filter, the color filter of the first roller differing in color from the color filter of the second or third roller. Each roller is also 110 provided with a separate diaphragm.

After the different parts of the device are

assembled and put in place, and after the proper light is provided for, then the handle 24 of the driving gear wheel 11 (illustrated in Figs. 2 and 4) is turned in the direction 5 of the unfeathered arrow. This driving gear 11 is in mesh with the stationary rack 12, fastened to the base 1, and therefore moves the movable frame work 2 in the direction of the feathered arrow and revolves 10 at the same time the three sensitized rollers through the shafts 9 and 10 operatively related to each other through the intermediate gearing. This gearing is so arranged that when through the movement of the movable 15 frame work the complete color surface has been brought into the optical field of the lens systems, the sensitized rollers will have made one complete revolution. The diaphragms 4, 4^a and 4^b perform the function of limiting 20 the optical field of the lens systems 6, 6^a and 6^b, as is clearly shown by dot and dash lines in Figs. 2, 4 and 5. Such arrangement is necessary for the purpose of photographing 25 a plane surface onto a movable cylindrical surface, to prevent distortion of the color images when photographed on the rollers. With a system as described, a true copy of 30 the color surface will be photographically impressed upon the rollers, but as the first of the rollers is provided with a color filter allowing only red rays to filter through, and the second with a filter allowing only green rays to filter through and the third with a filter allowing only blue-violet rays to filter 35 through, it is obvious that one roller will have photographed thereon the images (so to speak) of the red, the second roller of the green and the third of the blue-violet. As stated above, when the movable frame work 40 2 has completely brought the whole color surface 13, into the optical field of the lenses, then each of the sensitized rollers has made one complete revolution and each of these 45 rollers has therefore photographed thereon the images of the selected color of the whole color surface 13.

To more clearly describe the mode of operation and its practical working, it is supposed that only one roller is employed and 50 this roller is provided with a red filter. In its course of travel over the surface to be photographed, it will have, photographically speaking, impressed thereon at the start the first line of dots or squares of this 55 surface and will then during the course of travel and by its own rotation during said travel, have photographically impressed thereon successive lines of said dots or squares till through the whole entire revolution of this roller corresponding with the 60 line of travel over the whole surface to be photographed, all the lines of squares or dots composing the whole surface to be photographed are impressed one after the other 65 on said roller, but as said roller is provided

with a red filter only such dots or squares will be photographically impressed on this roller as correspond to the color of said filter. It is now supposed that two rollers are employed, the second roller following the 70 first roller and it is supposed that the second roller is provided with a green filter. At the start only the first roller or the roller provided with the red color filter will have impressed thereon, always photographically 75 speaking, the red dots or squares of the first line of the surface to be photographed and when then the first roller advances to a pre-determined distance, photographing thereby the dots or squares of succeeding lines, the 80 second roller will come in the field of vision of the first line and will have impressed thereon, photographically speaking, the green dots or squares of said first line and if a third roller is employed and this third 85 roller is provided with a blue-violet color filter, this roller will, if the advancement of the first and second rollers are far enough, come in the field of vision of the first line and will have, photographically speaking 90 again, impressed thereon the dots or squares of the first line corresponding to the color of its own filter and if—as stated above—the frame work advances and through this advancement each of the rollers revolve, it is 95 obvious that each of the rollers will in succession have photographically impressed thereon the squares or dots corresponding to its own filter of each succeeding line until the entire surface has been, photographically speaking, traversed and the last roller has had photographically impressed thereon the corresponding dots or squares of the last line of the surface to be photographed. Preferably, without taking the rollers out of 100 their frames, they are then developed in the usual manner, and are then, by preference, etched for the purpose later on to be used as printing rollers. It is obvious that from 105 these rollers, either by photographic or mechanical means, copies may be made on other rollers.

To reproduce the color scheme of the color surface as illustrated in Fig. 1, on a film with the aid of these rollers, it is only necessary to provide each of the rollers with the required colored ink and print from same in the usual manner.

The great advantage of this system lies therein, that the placement of the different 120 colors on the film will exactly correspond with the placement of these colors on the color surface 13 and will therefore represent an exact duplicate of this color surface.

Care has to be taken, that the color line at the beginning should blend, so to speak, in the color line at the ending so that the whole may represent a surface without demarcation.

In practice each individual color image 125

on the roller should be of comparatively small dimension, so that when the color scheme is printed on the picture film proper, each individual color image should, when 5 projected on the screen with the picture, not occupy a space larger than about one-sixteenth of a square inch. It is therefore obvious that when the color surface is photographed on the three rollers each of the color 10 images has to be suitably reduced.

Having now described my invention what I claim as new and desire to secure by Letters Patent is:—

1. In the art of color photography the 15 method which consists in first producing a series of images, differently colored, on a suitable surface, photographing then said images on a series of blanks suitably sensitized, each through a filter of different color, 20 developing the surfaces of said blanks in a manner so as to produce therefrom surfaces suitable for printing, and printing with said blanks simultaneously on a film later on to be used for photographic purposes, each 25 blank provided with a different color.

2. The method which consists in, first photographing a surface provided with the required color scheme on a series of rollers, provided each with a separate lens system 30 and filter of a different color, developing the photographed surfaces, and preparing the surface of each of said rollers for the process of printing.

3. The method which consists in: first providing a suitable surface with lines of dots or squares of required color value in required sequence, photographing then said dots or squares simultaneously on a series 35 of rollers suitably sensitized, developing then 40 said rollers and differentiating in height between the places acted upon by the rays of light and the places not acted upon by said rays.

4. In the art of producing color filters for

photographic blanks the steps which consist in securing a series of rollers mechanically as to each other, photographing on each of said rollers a multicolored screen, each roller through a different color filter and developing and preparing said rollers for the process of printing. 50

5. In the art of producing color filters for moving picture films the improvement which consists in providing the surfaces of a series of rollers with suitably sensitized layers, securing said rollers mechanically as to each other, photographing a color screen on each of said rollers with the interposition of a color filter differing for each of said rollers, developing said rollers and preparing then the surfaces of each of said rollers for printing purposes. 55

6. In the art of producing color filters for photographic blanks the method which consists in photographing on three rollers, mechanically connected to each other, and suitably sensitized, a series of different colored images each roller provided with a different color filter, developing then said rollers and preparing the same for the process of 60 printing. 70

7. In the process of producing with the aid of printing rollers color screens for photographic work the method which consists in first photographing on a series of rollers, 75 mechanically connected to each other, a series of lines of different colored images, each roller provided with a filter of different color, then developing said rollers and providing the same with a surface adaptable 80 for printing purposes.

In testimony whereof I affix my signature in presence of two witnesses.
